UNITED STATES PATENT OFFICE.

HENRY E. DECKEBACH, OF CINCINNATI, OHIO.

WORT-COOLER.

SPECIFICATION forming part of Letters Patent No. 527,197, dated October 9, 1894.

Application filed May 19, 1894. Serial No. 511,769. (No model.)

To all whom it may concern:

Be it known that I, HENRY E. DECKEBACH, a citizen of the United States, and a resident of Cincinnati, in the county of Hamilton and 5 State of Ohio, have invented certain new and useful Improvements in Wort - Coolers, of which the following is a specification.

My invention is an improved apparatus for cooling wort after it leaves the boiler and before it reaches the fermenting tuns. Its object is a simple compact device arranged to be interposed between the boiler and "hop jack," or between the boiler and fermenting tuns when the hop jack is not used, for reducing the temperature of wort without allowing its vapors to escape or the liquid to come in contact with the atmosphere, which is often laden with deleterious germs, spores, microbes, &c., in its passage from the boiler 15 to the fermenting vessels. By this means, also, the volatile oil of the hops, which imparts to malt liquors its delicate flavor, is not allowed to escape as the liquid is cooled below the temperature at which the oils become 20 volatilized before it leaves the cooling apparatus.

The invention will be first fully described in connection with the accompanying drawings and then particularly referred to and 25 pointed out in the claims.

Referring to the drawings, in which like parts are represented by similar reference letters wherever they occur throughout the various views: Figure 1 is a central longitudinal 35 section of the simplest form of my improved apparatus. Fig. 2 is an end elevation of the same. Fig. 3 is a sectional view taken in central longitudinal horizontal section of my apparatus having increased cooling surfaces.

Referring first to the simplest form of my invention, represented in Figs. 1 and 2, the outer case, A, is a plain cylinder, having a receiving branch, a, at its forward end to be connected to a discharge pipe (not shown) 40 from the hop jack, and a discharge branch, a', at the opposite end, which is to be connected to a pipe leading to the fermenting tuns. A flanged cast metal ring, a², is passed over the forward or open end of the cylinder, 45 A, and secured to the cylinder by a brazing, or in any suitable manner.

Within the cylinder, A, is a cylinder, B, the

open end of which is secured in a flanged ring, b. The rings, a² and b, are radially slotted to pass bolts, a³, which are pivoted between 55 lugs, a⁴, which lugs project from the rings, a². The two rings, a² and b, are detachably connected by these bolts and the wing nuts, a⁵. One end of the cylinder, B, is closed by a removable head or disk, b', which is held against 60 the ring, b, by bolts, b². These bolts also pass through the outwardly projecting flange, c, of the cap, C, and hold it in place.

To the inner end of the cylinder, B, is secured one end of a tube, D, which is spirally 65 coiled around the tube, B, to near its opposite end. The coil, D, terminates in a straight arm, which passes through the disk, b', and flange, c, and connects with the pipe, C', which pipe connects with the cap, C.

Within the cylinder, B, is a cylinder, E. The inner end of this cylinder is open and rests against the convex end of the cylinder, B. Near the inner end of this cylinder is a series of perforations to communicate with 75 the space between the outer wall of the cylinder, E, and the inner wall of the cylinder, B. The opposite end of the cylinder, E, is reduced and terminates in a tube, e, which extends centrally through the disk or head, 80 b', and the head or nut of the cap, C. The opening in the cap is provided with a packing gland, c', to prevent leakage around the tube, e.

The cooling liquid, from any suitable source, 85 is passed into the cylinder, E, through the tube, e, a portion of it passing into the space between the cylinders, B and E, through the perforations in the end of the cylinder, E, but the main portion passes through the coil, 90 D, and is discharged into the pipe, C', to be again returned to the source of supply, if desired, in the usual way.

The wort passes from the hop jack through the branch, a, thence around the cylinder, B, 95 in a spiral path controlled by the spiral coils of the tube, D, and passes out to the fermenting tuns through the branch, a'. When the hop jack or boiler is a sufficient distance above the cooling apparatus, gravity may be 100 relied upon to carry the wort through the cooler, but ordinarily an exhaust pump is interposed in the pipe between the cooler and the fermenting tuns.

When it is desired to cleanse the vessel, the wing nuts, a^5 , are unscrewed, the bolts swung back, and the tube, e , disconnected from its supply pipe, when the whole apparatus, inside of the cylinder, A , may be removed, and the coil and the inside of the cylinder, A , thoroughly cleansed. If it is desired to cleanse the inner cylinders, B and E , the bolts, b^2 , are removed, when the head or disk, b' , with the cylinder, E , may be removed and cleansed. There is a series of perforations, b^3 , made in the disk surrounding the tube, E , to allow the escape of the cooling liquid into the cap, C , and thence through the tube, C' .
 15 I have shown the apparatus in a horizontal position, supported upon a truss, F , having circular seats, f , upon which the cylinder, A , rests, and supporting legs, f' , which may be secured to the floor; but the apparatus may
 20 be suspended in hangers from the ceiling, if desired, and in some cases, where it is desirable to economize space, the apparatus may be placed in a vertical position.

It will be seen that there is no fitting required, as the coil, D , supports itself and cylinder, B , in proper position, and the inner cylinder, E , is supported at its inner end by bearing against the concave end of the cylinder, B . The joints between the rings, a^2 and b ,
 30 and head, b' , may be made close by a suitable packing, or by being dressed off true.

The form of my invention shown in Fig. 3 is provided with a double set of cooling coils and cooling jackets, adapted to receive the
 35 cooling liquid from two sources of supply, the wort being compelled to travel in a spiral path around both sets of coils and in contact with the cooling surfaces of the double sets of cylinders.

40 Briefly described, there are two jackets or chambers for two sets of coils, with but one continuous passage for the wort in the spiral path around both sides, practically doubling the cooling capacity of the apparatus without occupying additional space. The outer cylinder, A' , and the inner cylinder, B' , are connected together at their forward ends by flanged rings, a^6 and b^4 , same as in Fig. 1, leaving a jacket between the two cylinders
 45 for the coil, D' .

Within the cylinder, B' , is a cylinder, G , which has around it a ring, g , which comes opposite a similar ring, b^5 , on the extended end of the cylinder, B' , the two being bolted
 50 together, keeping the cylinders, G and B' , apart, to form the jacket between them. The inner end of the cylinder, B' , is contracted to pass within a grooved ring or casting, g' , the ends of the cylinders, B' and G , entering
 55 the groove in this ring and being brazed or soldered to it.

g^2 , is a ring which is bolted onto the grooved ring g' , to close the end of the jacket between the cylinders G and B' .

60 Within the cylinder, G , is the central cylinder, E' , having a reduced neck like the cylinder, E , in Fig. 1, to pass through the head,

g^3 , which closes the end of the cylinder, G , said cylinder having a flanged ring, g^4 , to which the head, g^3 , is bolted.

70 H , is a coil wound spirally around the cylinder, E' , in the jacket formed between said cylinder and the cylinder, G .

All the coils in my apparatus are made to just snugly fit the jackets between the cylinders, so that the wort is compelled to travel
 75 in the spiral path between the coils and in contact with the cylinders.

The cooling liquid from one source of supply enters the cylinder, E' , through the pipe, e' , passes to the opposite end of the cylinder, thence into the coil, H , through which it is discharged through the pipe, h , which passes through the head, g^3 , of the cylinder, G . The cooling liquid from the other source of supply
 80 passes into the coil, D' , through the pipe, d' , which passes through the outer shell, A' , through the flanged ring, b^4 , and connects with the coil. After passing through the coil to the inner end of the cylinder, B' , the opposite end of the coil communicates with the jacket between the cylinders, B' and G , and is discharged through the pipe, b^6 .
 85

The wort passes from the boiler or hop jacket through the pipe, a^7 , thence in the
 90 spiral path between the coils of cylinders, B' and G , from which it passes through the rings, g^1 and g^2 , into the space, a^8 , between the rings and the end of the cylinder, A' ; thence in the spiral path between the coils of the pipe, D' , in contact with the outer wall
 95 of the cylinder, B' , and inner wall of the cylinder, A' , and is discharged through the pipe, a^9 , leading to the fermenting tuns.

The apparatus, with the exception of the flanged rings which connect the cylinders, is
 100 made of copper, and the purpose of bolting the cylinders together in the manner shown, is to render them readily detachable for
 105 cleansing, or removing any scales or sediment that may adhere to the surfaces, with which the wort may come in contact.

In practice, I have found that the device, for a brewery of medium capacity should be in about the following proportions: about
 110 ten feet long; the outside shell thirteen inches in diameter; the cylinder next within it ten inches; the cylinder, G , seven inches and the inner cylinder four inches; the coils being one and one-half inches in diameter, so as to
 115 snugly fit the spaces between the cylinders, in order to retard the travel of the wort and keep it in contact with the cooling surfaces a sufficient time to reduce the temperature to the desired degree for entering the fermenting tuns; but it is obvious that the proportions
 120 may be varied, owing to the capacity of the brewery, and the simple form shown in
 125 Figs. 1 and 2 has been found sufficient for a brewery of small capacity and, of course, this form may be duplicated and used instead of the form shown in Fig. 3, but would of course
 130 occupy more space. It is also obvious that the cap, C , may be dispensed with, as its prin-

cipal object is to conduct the cooling liquid from both the coil and the jacketed spaces around the central tube to the central discharge pipe, C', in which case an opening could 5 be made in the head, b', and the branch of the pipe, C', connected to said opening by a suitable coupling; but the form shown is deemed the best, as the cooling liquid, after being partially heated by the passage of the 10 wort, would pass out at all points around the neck of the induction pipe, instead of being compelled to flow through a single opening below it.

What I claim as new, and desire to secure 15 by Letters Patent, is—

1. The combination, in a wort cooler, of the outer and inner cylinders separated from each other to form jackets for the passage of the wort and the cooling liquid, a spiral coil 20 within the wort jacket for the cooling liquid, said coil and the walls of the jacket being in close proximity to retard the movement of the wort through the jacket and keep it in contact with the cooling surfaces, the central 25 cylinder for the cooling liquid, communicating with the coil, induction and eduction pipes communicating with the wort jacket, and similar pipes to receive the cooling liquid into the device and discharge it therefrom; substantially as shown and described.

2. The combination of the outer cylinder, having closed ends, an inner cylinder forming, with the outer cylinder, a closed jacket for the passage of wort, a central cylinder 30 separated from the cylinder forming the inner wall of the wort jacket, having a reduced neck passed to the outside of the cooler, and separated from the surrounding cylinder, but communicating with it through perforations 40 in the inner end of said central cylinder, the inner and intermediate cylinders together forming a jacket for the cooling liquid, the cooling coil connected to the end of the intermediate cylinder and coiled around in the wort jacket, 45 said coil in proximity to the walls of the jacket to compel the wort to travel in a spiral path, an induction pipe at one end of the said wort jacket, and an eduction pipe at the opposite end, to connect with the pipe leading 50 to the fermenting tuns, a pipe to introduce cooling liquid to the inner cylinder, and a discharge pipe leading outside of the cooler for said cooling liquid after it has passed through the inner cylinder and coil, substantially as shown and described.

3. In a wort cooler, the combination of the outer case or cylinder, A, having induction branch, a, and eduction branch, a', the flanged ring, a², at one end of said cylinder, the inner cylinder, B, having flanged ring, b, for coupling the inner and outer cylinders, and closing the jacketed space between them, the spiral coil, D, connected to the inner end of the cylinder, B, coiled around it toward the 60 opposite end, and having a branch passing to the outside of the cooler, the inner cylinder, E, having a reduced neck passing through

the end of the cooler to receive the pipe conveying the cooling liquids, said cylinder, E, being open at the inner end and bearing 70 against the end of the intermediate cylinder, B, and having its end perforated to pass portions of the cooling liquid from the cylinder, E, around the space in the jacket between it and the cylinder, B, the head, b', closing the 75 end of cylinder, B, and perforated to pass the cooling liquid from the jacketed space between the cylinders, E and B, substantially as shown and described.

4. In a wort cooler, the combination of the 80 outer cylinder, having induction pipe at one end and eduction pipe at the other, flanged ring around the open end of said cylinder, an inner cylinder having flanged ring closing the jacket between the said cylinder and the outer 85 cylinder, bolts and nuts for detachably securing the two cylinders together, perforated heads secured to the front end of said intermediate cylinder, a central cylinder having reduced neck passing centrally through said 90 head, having its inner end open to bear against the concavo-convex end of the surrounding cylinder and perforations communicating with the jacket between the inner and intermediate cylinders, the cap, C, surrounding 95 the reduced neck of the inner cylinder, the cooling coil, D, connected to the inner end of the intermediate cylinder and coiled around said cylinder at the forward end, forming a spiral path in the jacket between the intermediate and outer cylinders, the discharge pipe, C', for the cooling liquid, communicating with the space between the inner and intermediate cylinders, and the branch in the coil passing through the head of the inner 100 cylinder and communicating with said discharge pipe, whereby the wort is compelled to travel in a spiral path in the jacketed space between the outer and intermediate cylinders, and the cooling liquid passed to the inner 105 cylinder and from there partly through the coil and partly in the space or jacket between the inner and central cylinders, substantially as shown and described.

5. The combination of the outer cylindrical 115 case a central cylinder, having its open end protruding through the end of said case, double cylinders intermediate the central cylinder and outer case, said intermediate cylinders being closed at their ends to form a jacket 120 for the cooling liquid, and said cylinders forming communicating wort jackets between the outer case and intermediate cylinder, and the intermediate cylinder and central cylinder, the wort supply pipe connected to the inner 125 jacket, the wort discharge pipe leading from the outer jacket, cooling coils in both the inner and outer wort jackets, a supply pipe for the outer coil, the opposite end of said coil connected to discharge into the jacket between the intermediate cylinders, the discharge pipe leading from said jacket at its forward end, said inner coil connected to the inner end of the central cylinder to receive

the cooling liquid from it, and the opposite end of said inner coil passing to the outside of the cooler, and a supply pipe for the cooling liquid connected to the front end of the central cylinder, substantially as shown and described.

6. The combination of the outer cylindrical case, the central cylinder having its open end protruding through the end of said case, the two cylinders closed at their ends intermediate the central cylinder and outer case, and detachably connected to the outer case and to each other at their inner ends by ringed flanges opening communication between the spaces or jackets between the inner cylinder

and intermediate cylinder, and between said intermediate cylinder and the outer case, cooling coils in said jackets, the inner coil communicating with the central cylinder and the outer coil communicating with the jacket 20 between the intermediate cylinders, the wort supply and discharge pipes communicating with said jackets, and the supply and discharge pipes for the cooling liquids, substantially as shown and described.

HENRY E. DECKEBACH.
